UNITED STATES PATENT OFFICE.

THOMAS C. RIDGE, OF CARTHAGE, ILLINOIS.

ATTACHMENT FOR RUBBER SHOES.

1,087,829.

Specification of Letters Patent. Patented Feb. 17, 1914.

Application filed September 6, 1912. Serial No. 718,901.

To all whom it may concern:

Be it known that I, THOMAS C. RIDGE, a citizen of the United States, residing at Carthage, in the county of Hancock and State of Illinois, have invented new and useful Improvements in Attachments for Rubber Shoes, of which the following is a specification.

This invention relates to improvements in retainers for rubber overshoes and has for its objects to provide a retainer which may be conveniently secured or detached from the overshoes.

In carrying out my invention it is my purpose to provide a device of this character which will be of a simple construction, cheap to manufacture, easily applied and which will perform the functions for which it is devised with ease and with certainty.

With the above recited objects in view and others which will appear as the nature of the invention is more fully understood, the improvement resides in the construction, combination and operative arrangement of parts set forth in the following specification and falling within the scope of the appended claim.

In the drawings, Figure 1 is a perspective view of an overshoe provided with the removable retainer. Fig. 2 is a central longitudinal section through an over shoe provided with my retainer and illustrating the position of the same upon the walking shoe. Fig. 3 is a detail perspective view of the retainer detached. Fig. 4 is a sectional view illustrating the manner in which the retainer will be connected with the overshoe.

Referring to the drawings in detail, the numeral 1 designates a shoe which has the opposite sides of the counter thereof provided with a series of openings 6.

A retainer 3, constructed of elastic material, is arranged within the overshoe adjacent the heel thereof and as shown, is provided with attaching portions or arms 5 engaging the inner surfaces of the sides of the counter, each of said arms being provided with a series of openings 6' registering respectively with the openings 6 in the sides of the counter of the overshoe so as to cause

the arms to slant upwardly and rearwardly in the direction of the heel of the overshoe. As shown the upper ends of the arms are connected to each other by an intermediate loop 5', which loop, as illustrated in Figs. 55 1 and 2, is disposed above the upper edge of the heel of the overshoe and spaced therefrom, and is adapted, when the overshoe is applied to the ordinary shoe, to engage against the shoe at a point directly above 60 and in contact with tendon achilles, so as to retain the overshoe in its applied position upon the ordinary shoe. Extending through the said registering openings at the outer surface of the overshoe and adapted to detachably secure the attaching portions of the retainer to the counter of the overshoe are headed screw members 8, the bore of each screw being threaded and being adapted to coact with the threaded stem 9 of a headed 65 member 10. The heads of one or both of the members 8 and 10 may be depressed as at 11 to provide for the reception of an edged tool, such as a screw driver and whereby the said members 8 and 10 may be easily secured 70 together to compress the arms 5 and the overshoe 1 between the heads of the said members 8 and 10.

While the device has been described in connection with overshoes, it is of course to 80 be understood that the same may be employed with equal efficiency upon slippers, low cut shoes, dancing pumps and other foot wear.

From the above description, taken in connection with the accompanying drawings, the simplicity of the device as well as the advantages thereof, will, it is thought, be perfectly apparent to those skilled in art to which such inventions appertain without 85 further detailed description.

Having thus described the invention, what I claim is:—

The combination with an overshoe, of a retainer, said retainer being formed of elastic material and comprising attaching portions and an intermediate loop, said attaching portions being provided with openings, openings in the opposite sides of the counter of the overshoe adapted to register with the 100

openings in said attaching portions, and fastening means adapted to extend through the openings in the sides of the overshoe and the corresponding openings in the attaching portions of the retainer and detachably secure said attaching portions to the opposite inner sides of the overshoe, said retainer when so secured slanting rearwardly with

said loop in position to engage the rear portion of the inner shoe. 10

In testimony whereof I affix my signature in presence of two witnesses.

THOMAS C. RIDGE.

Witnesses:

J. P. GUTHRIE,
A. M. PAGETT.
